UNITED STATES PATENT OFFICE.

AUBREY HOUSTON, OF CHRISTCHURCH, AND HENRY PERMAIN STEPHENSON, OF ASHBURTON, NEW ZEALAND.

LOCKING DEVICE.

1,418,571.

Specification of Letters Patent. Patented June 6, 1922.

Application filed July 26, 1920. Serial No. 399,122.

To all whom it may concern:

Be it known that we, AUBREY HOUSTON and HENRY PERMAIN STEPHENSON, subjects of the King of Great Britain and Ireland, 5 residing in Christchurch and Ashburton, respectively, New Zealand, have invented a new and useful Improvement in Locking Devices; and we do hereby declare the following to be a full, clear, and exact description of the same.

This invention relates to locking devices of the keyless or combination type, and is adaptable for various purposes.

The object of the invention is to provide 15 a lock that can be readily operated by a person knowing the correct combination and that will be effective against operation by unauthorized persons, and in which the combination is automatically thrown out of register by either the locking or unlocking of 20 the device.

According to our invention, discs or similar circular members are mounted upon a spindle and arranged one above the other 25 thereon or upon separate spindles. Each disc is provided with a slot or groove into which slot or groove pins from a lever which is pivoted in a suitable position are adapted to enter. The slots are arcuate or approxi- 30 mately arcuate for the radial movement of the lever for a part of their distance and are then shaped so that the discs may wholly or partially revolve independently of any movement of the lever. Upon one or both of the 35 discs is fixed a pinion adapted to mesh with toothed sections upon the lever. The pinion or pinions has or have teeth at the required intervals with which the toothed sections mesh in such a manner that after the pins 40 have entered the slots the discs will be caused to revolve and upon the opposite movement of the lever after the pins have left the slots, the discs will be caused to rotate by means of a toothed section or sec- 45 tions engaging in a toothed section of the pinion or pinions upon a disc or discs, the arrangement being such that the pins are thrown out of register with the slots and upon any further rotation of the discs the 50 pins ride upon the periphery thereof.

The mechanism is suitably housed and the spindles provided with dials, the circumferences of which are divided into a number of divisions, preferably as a clock face, and as 55 each dial is fixed by the medium of the spin-

dle or sleeve to a disc, it follows that each dial must be in a pre-determined position before the slots register with the pins upon the lever. The dials, however, are adjustable to different positions upon their respective spindles or sleeves, thus permitting all the points of the dials being changed in relation to each other and to the point of registering of the slots and pins and enabling a multiplicity of combinations of the 60 dials being made. The lever may be operated by any suitable means, such as a knob or button extending through the housing and the lever may be provided with contacts for closing an electric circuit or may be ex- 65 tended to form a locking bolt in any convenient manner.

On the drawings:—

Figure 1, is an elevation.

Figure 2, is a sectional elevation of the 75 device in the form of a switch box for motor vehicles.

Figure 3, is a cross section on line 3—3, Figure 2.

Figure 4, is a sectional elevation, showing 80 the parts in a different position.

Figure 5, and

Figure 6, are views showing the discs in different operated positions.

Figure 7, is an elevation of a modified 85 form of device.

Figure 8, is a cross section on line 8—8, Figure 7.

Figure 9, is a view of a detail.

Referring to the drawings, and more par- 90 ticularly to Figures 1 to 6 inclusive, discs 1 and 2, of which the disc 1 is fixed to a spindle 3 and the disc 2 is fixed to a sleeve 4 freely mounted on the spindle 3, so that they

rotate independently of each other. The 95 disc 1 has a slot 5 and the disc 2 a slot 6, or the discs may be grooved as in Figure 9 so as not to unduly weaken them. Pins 7 and 8 project from a lever 9 which is pivoted in the framing by a spindle 10 and are adapted 100 to enter the slots 5 and 6 respectively. These slots have a radius from the axial point of the lever 9 for a part of their distance, and are then shaped as shown in order that the discs may rotate a limited extent independently of the movement of the lever. Fixed to the spindle 3 is a pinion 11 adapted to ro- 105 late with the disc 1, the teeth of which are cut-away at 12 and 13. The teeth of the pinion are adapted to mesh with a tooth 16 110

- and with teeth 17 upon a quadrant portion of the lever 9. An arm 18 projects from the lever 9 and is adapted to engage with pins 19 near the circumferential periphery of the disc 2.
- 5 This arm 18 engages the pins 19 after the pin 8 has entered the slot 6 and rotates the disc 2, the slot being shaped as shown in Figure 6 to admit of the rotation of the disc 2 during the inward movement of the arm.
- 10 Another arm 20, also projecting from the lever 9, engages a pin 21 upon the disc 2 and rotates the said disc when the lever is clear of the slots. The spindle 3 is pivoted in walls 22 and 23 spaced apart by and supported on pillars 24 as indicated in Figure 3. Pawls 25 and 26 pivoted on pins 27 to the walls 22 and 23 respectively, engage in the serrated peripheries of wheels 28 and 29 fixed respectively to the discs 1 and 2. The 15 pawls are retained against the serrations by means of springs 30 and 31 secured upon one of the pillars 24, as shown in Figures 2 and 3. This gives the necessary braking action or tension upon the discs.
- 20 A dial 32 is fixed upon the sleeve 4 by means of a set screw 33 while another dial 34 is fixed upon the spindle 3 by a screw 35. The dial 32 has an operating knob or pin 36 and the dial 34 an operating knob 37. The 25 dial 32 has marked upon its outer circumferential edge a number of divisions preferably corresponding to the divisions upon a clock face, with similar markings upon the inner circumferential edge, as indicated in Figure 1, while the dial 34 has a pointer 38 fixed to or marked upon the dial.

In the figures the device is shown in the form of a switch box for motor vehicles and for locking the switch thereof in its cut off position, and for this purpose the lever 9 is provided with contacts 40 and 41 to make contact with terminals 42 and 43 respectively, the lever 9 being controlled by a button 44 which fits on to the spindle 10 or to 40 any other convenient portion of the lever 9. The terminals pass through an insulated piece 45 to which the wall 22 is secured.

A suitable casing 46 encloses the mechanism and may be bolted or locked in position 50 on the car in order to prevent it being readily removed or interfered with.

The operation of the device will now be described.

The dials are previously adjusted to a pre-55 determined combination by means of the set screws 33 and 35. For example, the dial 32 is set so that the "12" is opposite the mark 48 on the casing 46 and so that the slot 6 will be in a position as shown in Figures 2 and 60 6 for the pin 8 to enter. The dial 34 is then set, for example, so that the pointer 38 is opposite to the "3" on the dial 32, the slot 5 being then in a position for the pin 7 to enter. The operator then, for convenience, 65 can remember the combination as twelve

o'clock and three o'clock. Any of the divisions between these numbers may be selected, such as minutes or half minutes.

In Figure 2, the lever 9 is shown in a position corresponding to the position in 70 which the dials are set in Figure 1, whereby the pins 7 and 8 may enter the slots 5 and 6. Upon the lever being operated in the direction of the arrow the pin 7 will travel along the slot 5 and the pin 8 along the slot 6 until 75 the teeth 17 engage the teeth of the pinion 11 when the pinion and the disc 1 will be rotated until the lever assumes the position shown in Figure 4, and contact is made between the contacts and terminals. At this 80 point a tooth upon the pinion 11 will engage against the shoulder 50 of the lever and prevent any further rotation. The disc 2 will at the same time have been rotated by the arm 18 engaging with the pins 19, thus 85 both the discs are rotated thereby changing their positions and the position of the dials in order that the required combination will not show when the switch is on.

In the position of Figure 4, the contacts 90 40 and 41 are in contact with the terminals 42 and 43 and when it is desired to switch off the current the lever is moved in the direction of the arrow in Figures 4 and 5, the teeth 17 rotating the disc 1 and the arm 18 95 rotating the disc 2 in order to permit the lever to return to the position shown in Figures 2 and 6. The discs are then free to rotate and by moving the lever to its full extent in the direction of the arrow shown 100 in Figures 4 and 5, the teeth 17 of the quadrant will engage with the teeth of the pinion 11 and rotate the disc 1 and when the position in Figure 5 is reached a tooth 51 adjacent to the tooth 16 will carry the teeth 17 clear of the teeth of the pinion so that the lever 9 may be returned to the positions in 105 Figures 2 and 6 without engaging the teeth of the pinion. The arm 20 will engage with the pin 21 on the disc 2 also rotating that 110 disc until the position shown in Figure 5 is reached. Thus the discs will have been moved so as to prevent the pins 7 and 8 again entering the slots 5 and 6 until the discs are rotated to their correct positions, 115 and also rotating the dials so that the correct combination does not appear. By moving the lever 9 back until the pins 7 and 8 rest upon the periphery of the discs and the button 44 indicates the locked position, 120 the pins will ride upon the circumferential periphery of the discs while the discs themselves are free to rotate and the lever can only be moved to the "on" position when the discs are brought to register with the pins 125 7 and 8.

In Figure 7, is shown a modified form of the device. In this case discs 54 and 55 corresponding to the discs 1 and 2 are pivoted upon pins 56, each disc being connected 130

to a dial 57. The discs 54 and 55 are provided with teeth 58 into which teeth 59, corresponding with the teeth 17, are adapted to gear and rotate the discs. These teeth 59 are arranged upon a wheel 60 pivoted upon a pin 61 and is fixed to a lever 62 having the same function as the lever 9 such lever 62 being pivoted on the pin 61 which is fixed in an insulated base 66. The ends of the lever have pins 63 and 64 adapted to enter the slots in the discs. The wheel 60 also has teeth 65 which correspond and operate in the same way and for the same purpose as the teeth 17 and the arms 18 and 20. Instead of engaging with teeth they may simply engage with pins as shown in Figures 5 and 6, and in the same way, instead of using pins as shown in these figures, teeth may be used. The discs 54 and 55 may be of insulating material while the pins 56 are connected to electrical terminals connection being made between the terminals by the lever 62 contacting with the pins. The lever may be operated in the same manner as the lever 9. The operation of this will be clear from the operation of the device shown in the previous figures.

If employed as a lock the end of the lever or any convenient part of the levers 9 and 62 can simply be extended to form a locking bolt either as a bolt itself or to operate a locking bolt of a lock.

It is obvious that more than two discs, operating mechanism and dials for each disc may be employed, thereby still further increasing the safety and efficiency of the device.

To prevent the mechanism being strained by futile attempts to move the lever when in the position shown in Figures 2 and 6, a locking device is preferably provided consisting of a catch 68 fixed on a spring member 69 fixed to a convenient part of the framing, Figure 2 showing it fixed to the wall 22 and Figure 8 showing it fixed to the wall 70.

A press button 71 is connected to one end of the spring member for operating the catch. When the lever 9 is in the position shown in Figure 2 or the lever 62 in the position shown in Figure 7, such levers will engage against the catch and prevent the movement of the lever and the pins entering the slots until such time as the press button 71 has been operated.

The dials may, if desired, be enclosed beneath glass and may be operated by means of a milled knob adapted to operate the dials through the medium of suitable toothed wheels.

The dials may be made luminous in order to be easily adjusted by night.

What we claim and desire to secure by Letters Patent of the United States is:—

1. In a device of the kind described, a frame, discs rotatably mounted on said

frame, slots or grooves in said discs, pins adapted to enter said slots or grooves, a lever pivoted in said frame from which lever said pins project, means whereby upon operating said lever in either direction the discs 70 are caused to rotate, means whereby when the lever is moved clear of the discs said discs will be rotated and the pins prevented from entering the slots, dials attached to each of said discs, said dials having marks 75 or divisions to coincide with corresponding positions of the slots, and a member against which said lever engages in order to prevent said lever being operated and to prevent the said pins entering said slots until 80 said member has been operated to disengage said lever therefrom, substantially as set forth.

2. In a device of the kind described, a frame, discs rotatably mounted on said frame, slots or grooves in said discs, pins adapted to enter said slots or grooves, a lever pivoted in said frame from which lever said pins project, means whereby upon operating said lever in either direction the discs are 90 caused to rotate, means whereby when the lever is moved clear of the discs said discs will be rotated and the pins prevented from entering the slots, dials attached to each of said discs, said dials having marks or divisions to coincide with corresponding positions of the slots, substantially as set forth. 95

3. In a device of the kind described, a frame, circular members rotatably mounted in said frame and having arcuate slots or 100 grooves therein, a pivoted member, pins on said pivoted member adapted to enter and travel along the slots, means whereby when said lever is operated in either direction the circular members are caused to rotate, the 105 slots being shaped to permit of such rotation, means upon said pivoted member to rotate said discs, means to prevent said pins entering the slots when the device is locked, dials rotatable with said discs, means for 110 adjusting said dials so that when a pre-determined point upon said dials corresponds with a fixed or pre-determined point the slots will register with said pins, and means for operating said dials, substantially as set 115 forth.

4. In a device of the kind described, a frame, discs rotatably mounted in said frame and having arcuate slots or grooves therein, a pivoted lever, pins projecting from said 120 lever adapted to enter the slots or grooves, pinions upon said discs, teeth upon said lever adapted to gear with the teeth of said pinions, the teeth of the pinions and the teeth of the said lever being so arranged 125 that when the lever is operated the pins enter the slots in said discs and the discs are caused to rotate and upon movement of the lever after the pins have left the slots the discs will also be caused to rotate, dials fixed 130

to the said discs and marked with divisions whereby they may be adjusted to a pre-determined position to coincide with the position of the slots when they register with the 5 pins, substantially as set forth.

5. In a device of the kind described, an arcuate slotted disc, a spindle upon which said disc is fixed, a second arcuate slotted disc mounted freely on said spindle, a 10 toothed pinion fixed on said spindle, a pivoted lever, pins projecting from the ends of said lever adapted to enter the slots, sections of teeth in a quadrant portion of said lever, one section of said teeth being adapted 15 to engage said pinion and rotate the pinion and the disc after said pins have entered the slots, another section of teeth upon said lever adapted to rotate said pinion and disc after said pins have left the slots, means

upon said lever to rotate said second disc 20 after the pins have entered the slot and to rotate said disc after the said pin has left the slot, tension means for said discs, a dial fixed to said second disc, another dial fixed to the spindle, said dials having circumferential divisions, and means for adjusting the dials so that one set of divisions may be set to coincide with the position that the slots register with the pins, substantially as set forth. 25

30 In testimony whereof we have signed our names to this specification in the presence of two subscribing witnesses.
